UNITED STATES PATENT OFFICE.

WOODFORD A. KIPER, OF CARROLLTON, KENTUCKY.

VENTILATING ARCH SUPPORT.

Application filed May 29, 1923. Serial No. 642,251.

To all whom it may concern:

Be it known that I, WOODFORD A. KIPER, a citizen of the United States, residing at Carrollton, in the county of Carroll and

5 State of Kentucky, have invented certain new and useful Improvements in Ventilating Arch Supports, of which the following is a specification.

This invention relates to ventilating arch supports and has for an object to provide 10 a device attached to or occurring upon the bottom of shoes adapted at each step of the wearer to be collapsed to force a current of air, medicated or otherwise, into the shoe, 15 also to be constructed of such material as to in itself support the arch under which it is located.

A further object of the invention is to provide a hollow support secured to or occurring 20 beneath the arch of a shoe of such proportion that it engages the ground before both the heel and the sole, whereby the step of the wearer is placed first upon the arch support, collapsing the support and 25 also employing its resiliency as a support for that portion of the foot.

A further object of the invention is to provide a hollow elastic device secured below the arch of a shoe either integral with 30 the heel or separate therefrom, having a chamber communicating with the interior of the shoe by means of a perforation through the arch, with facilities within the chamber of the arch support for maintaining medicament introduced therein to deliver the fumes or volatile ingredients 35 through the perforation into the shoe.

With these and other objects in view, the invention comprises certain novel parts, elements, units, combinations, interactions and 40 functions, as disclosed in the drawings, together with mechanical and functional equivalents thereof, as will be hereinafter more fully described and claimed.

45 In the drawings:

Figure 1 is a view in side elevation of a shoe provided with the present invention.

Figure 2 is a fragmentary view of a shoe partly in side elevation, showing the shank 50 in longitudinal section; also the ventilating arch support in section.

Figure 3 is a transverse sectional view through the shank of a shoe and the ventilating arch support.

55 Figure 4 is a perspective view of the sev-

eral parts and units which make up one embodiment of the present invention.

Figure 5 is an inverted perspective view of the supporting member.

Figure 6 is a longitudinal sectional view 60 of the supporting member made integral with the heel.

Like characters of reference indicate corresponding parts throughout the several 65 views.

The improved ventilating arch support which forms the subject-matter of this invention comprises a resilient or elastic member, 10, having a chamber, 11, formed therein, secured to the under side of the shank, 70 12, of a shoe, with a perforation or vent, 13, through the shank of the shoe communicating at one end with the chamber, 11, and at the other end with the interior of the shoe and preferably, though not necessarily, produced by means of an eyelet, 14.

As will be noted especially from Figures 1, 2 and 3, this resilient or elastic member, 10, is so proportioned relative to the other parts of the shoe that it touches the ground 80 before the heel and sole of the shoe, whereby the weight of the wearer tends to collapse the member, 10, and therefore contract the chamber, 11. Preferably this member, 10, will be composed of rubber properly vulcanized to withstand wear and to yield to the pressure of the wearer but, nevertheless, to exercise a considerable degree of support under the arch, 12, of the shoe, whereby it becomes not only a device for contracting 90 the chamber at each step but serves also as an arch support.

In one embodiment of the invention, the member, 10, is provided with cuts, 15, in its opposite ends, as shown more particularly at Figure 4, and the frame, 16, preferably though not necessarily of metal, provided with end bars, 17, fitting into the cuts, 15, of the member, 10. Side flanges, 18, serve to clamp the member, 10, rigidly 100 therebetween and to prevent lateral distortion. The interval between the flanges, 18, may be such that the member, 10, may be forced into position with considerable pressure, whereby it is retained rigidly. This frame, 16, is nailed, riveted, or otherwise secured beneath the shank, 12, of the shoe, preferably with an elastic gasket, 19, interposed for the purpose of rendering the connection water-tight.

Within the chamber, 11, an absorbent member, 20, is positioned so that a medicament may be poured through the perforation, 13, to saturate this absorbent material 5 which will retain the medical properties until sufficiently aerated, such aeration passing through the perforation into the shoe.

Instead of making the member, 10, as a 10 separate member, it may be constructed, as indicated at 10' in Figure 6, integral with the heel, 21, and it is obvious that the invention is in no way limited to the specific 15 means for attaching the device to the shoe, as the integrality will tend to augment the attachment of the device, making it possible under some conditions to dispense with the frame, 16.

In use, the device will be secured beneath 20 the shank of the shoe which has previously been provided with the vent in such position that the vent is wholly covered by the chamber, 11. This chamber, 11, may or may not be first filled with the absorbent material, 20, depending upon whether the device is to 25 be used for applying medicinal properties to the foot or only for ventilation. In either case, the thickness of the device relative to the interval between the shank and the ground line will be such that at each 30 step the resilient or elastic material of the device will be put under compression, reducing the capacity of the chamber, 11, whereby air or medicated air from the chamber will be forced through the vent 35 into the shoe.

I claim:

1. The combination with a shoe embodying a heel and a sole connected by a shank having a perforation therethrough of a resilient member secured beneath the shank 40

and provided with a chamber in communication with the vent, said resilient member being proportioned to engage the ground line before the heel and sole.

2. The combination with a shoe embodying a heel and a sole connected by a shank having a vent therein of a ventilating support secured beneath the shank and provided with a chamber in communication with the vent and proportioned to be collapsed at each step of the wearer. 45 50

3. The combination with a shoe comprising a heel and a sole connected by a shank having a perforation therethrough of a chamber having resilient walls in communication with the perforation and having its lower limit extend downwardly below the line connecting the heel and sole. 55

4. A ventilating arch support comprising a resilient member having a cavity formed in its upper side producing a chamber and means to secure the support to the under side of a shoe shank. 60

5. A ventilating arch support comprising a device of resilient material proportioned to be interposed between the sole and heel and secured to the under side of the shank of a greater vertical dimension than the interval of the arch, said member being provided with the chamber formed in the side adapted to be connected to the shoe. 65 70

6. A medicating arch support comprising a resilient member having a chamber formed therein, an absorbent in the chamber and means to secure the device to the under side of a shoe previously provided with a vent therethrough.

In testimony whereof I affix my signature.

WOODFORD A. KIPER.
